UNITED STATES PATENT OFFICE

151,158

DESIGN FOR A HEATER

Ralph E. Kruck, Clinton, Conn., assignor to
Florence Stove Company, Gardner, Mass., a
corporation of Massachusetts

Application September 24, 1947, Serial No. 141,568

Term of patent 14 years

(Cl. D81—19)

To all whom it may concern:

Be it known that Ralph E. Kruck, a citizen of the United States, residing at Clinton, in the county of Middlesex, State of Connecticut, has invented a new, original, and ornamental Design for a Heater, of which the following is the specification, reference being made to the accompanying drawing, forming part thereof.

Fig. 1 is a front elevational view of a heater, showing my new design.

Fig. 2 is a side elevational view looking from the right of Fig. 1.

Fig. 3 is a plan view thereof.

The design of the left-hand side of the heater, as viewed from the left of Fig. 1, is the same as

that of the right side shown in Fig. 2, but with the various elements reversed.

I claim:

The ornamental design for a heater, as shown and described.

RALPH E. KRUCK.
